UNITED STATES PATENT OFFICE.

WILLIAM H. GRINDLEY, OF CONGLETON, ENGLAND, ASSIGNOR TO WILLIAM S. PITCAIRN, OF NEW YORK, N. Y.

DESIGN FOR A COVERED DISH.

SPECIFICATION forming part of Design No. 31,710, dated October 24, 1899.

Application filed September 29, 1899. Serial No. 732,113. Term of patent 3½ years.

To all whom it may concern:

Be it known that I, WILLIAM H. GRINDLEY, a subject of the Queen of Great Britain, residing at Congleton, county of Chester, England, have invented a new and original Design for a Covered Dish; and I do declare the following to be a full, clear, and exact description of the same, reference being had to the accompanying drawings, forming a part hereof.

10 In the drawings, Figure 1 is a top view of the covered dish embodying my design. Fig. 2 is a side view, and Fig. 3 an end view, of the same.

The body of the dish is oblong or oval. Its 15 upper rim is scalloped, a flat scallop alternating with rounder scallops. The dish is provided at each extremity with a handle and narrows sharply downward toward the base, which extends outward and is irregularly 20 scalloped along its lower rim.

Immediately beneath the upper rim of the dish and parallel therewith is a continuous band of embossed beads *a*. Beneath this band is a row of embossed ornamentalations alternately arranged, one being a star-like figure *b* and the other a branch or twig like figure *c*. Near the base is embossed a hori-

zontal row of scallops *d*, inclosing downwardly projecting lines *e*.

The cover of the dish is similar in outline 30 to the upper rim of the body of the dish, into which it fits and which it overlaps. The rim of the cover is ornamented with a continuous band parallel therewith of embossed beads *a*, and within this band is a row of embossed 35 ornamentalations alternately arranged, one being a star-like form *b* and the other a branch or twig like form *c*. In the middle of the cover are two raised portions *f* and *g*, with a depression between them, the handle being 40 placed at the top. At the base of the raised portion is an oblong band of embossed scallops *d*, inclosing inwardly-projecting lines *e*.

What I claim is—

The design for a covered dish substantially 45 as shown and described.

In witness whereof I have hereto affixed my signature, this 19th day of September, 1899, in the presence of two witnesses.

WILLIAM H. GRINDLEY.
